(57) **CLAIM**

The ornamental design for an intake manifold, as shown and described.

DESCRIPTION

FIG. 1 is a front, right, top perspective view of an intake manifold, showing my new design;

FIG. 2 is a rear, left, bottom perspective view thereof;

FIG. 3 is a rear, left, top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of detail 10 in FIG. 4;

FIG. 11 is an enlarged view of detail 11 in FIG. 4;

FIG. 12 is an enlarged view of detail 12 in FIG. 7;

FIG. 13 is an enlarged view of detail 13 in FIG. 9; and,
FIG. 14 is a rear, left, top perspective view of its reduced scale in a detached state.

The dashed broken lines in the figures are for the purposes of illustrating portions of the intake manifold and form no part of the claimed design.

The dash-dot-dash broken lines are for notating enlarged views and form no part of the claimed design.

The dash-dot-dot-dash lines represent boundaries, and form no part of the claimed design.
